UNITED STATES PATENT OFFICE.

ROBERT L. HATFIELD, OF NEWARK, NEW JERSEY.

DESIGN FOR AN EMBLEM, BADGE, PIN, FOB, RING, OR LIKE ARTICLE.

55,041.

Specification for Design.

Patented May 4, 1920.

Application filed June 14, 1918. Serial No. 240,082. Term of patent 14 years.

To all whom it may concern:

Be it known that I, ROBERT L. HATFIELD, a citizen of the United States, residing at Newark, in the county of Essex and State of New Jersey, have invented a new, original, and ornamental Design for an Emblem, Badge, Pin, Fob, Ring, or like Article, of which the following is a specification, reference being had to the accompanying drawing, forming part hereof, in which

The figure is a plan view of an emblem, badge, pin, fob, ring or like article showing my new design.

The design comprises a substantially

equilateral triangular-shaped field, within which the letter "V" is so arranged as to divide said triangular field into a substantially diamond-shaped portion and two substantially equilateral triangular portions. Said diamond-shaped portion is produced in white, one of said triangular portions is produced in red, and the other of said triangular portions is produced in blue.

I claim:

The ornamental design for an emblem, badge, pin, fob, ring, or like article, as shown.

ROBERT L. HATFIELD.
